[57]**CLAIM**

The ornamental design for a flower pot cover, as shown and described.

DESCRIPTION

FIG. 1 is a perspective view of our new flower pot cover design;

FIG. 2 is a side elevational view of the left side thereof;

FIG. 3 is a side elevational view of the right side thereof;
FIG. 4 is a side elevational view of the front side thereof;
FIG. 5 is a side elevational view of the back side thereof;
FIG. 6 is a top plan view thereof;
FIG. 7 is a bottom plan view thereof;
FIG. 8 is a perspective view of a second embodiment of our new flower pot cover design;
FIG. 9 is a side elevational view of the left side thereof;
FIG. 10 is a side elevational view of the right side thereof;
FIG. 11 is a side elevational view of the front side thereof;
FIG. 12 is a side elevational view of the back side thereof;
FIG. 13 is a top plan view thereof;
FIG. 14 is a bottom plan view thereof;
FIG. 15 is a perspective view of a third embodiment of our new flower pot cover design;
FIG. 16 is a side elevational view of the left side thereof;
FIG. 17 is a side elevational view of the right side thereof;
FIG. 18 is a side elevational view of the front side thereof;
FIG. 19 is a side elevational view of the back side thereof;
FIG. 20 is a top plan view thereof;

FIG. 21 is a bottom plan view thereof;
FIG. 22 is a perspective view of a fourth embodiment of our new flower pot cover design;
FIG. 23 is a side elevational view of the left side thereof;
FIG. 24 is a side elevational view of the right side thereof;
FIG. 25 is a side elevational view of the front side thereof;
FIG. 26 is a side elevational view of the back side thereof;
FIG. 27 is a top plan view thereof;
FIG. 28 is a bottom plan view thereof;
FIG. 29 is a perspective view of a fifth embodiment of our new flower pot cover design;
FIG. 30 is a side elevational view of the left side thereof;
FIG. 31 is a side elevational view of the right side thereof;
FIG. 32 is a side elevational view of the front side thereof;
FIG. 33 is a side elevational view of the back side thereof;
FIG. 34 is a top plan view thereof; and,
FIG. 35 is a bottom plan view thereof.
